UNITED STATES PATENT OFFICE.

HENRY K. CLEMENT, OF LAPORTE, INDIANA.

GRAIN-SIEVE.

SPECIFICATION forming part of Letters Patent No. 677,857, dated July 9, 1901.

Application filed September 1, 1900. Serial No. 28,839. (No model.)

To all whom it may concern:

Be it known that I, HENRY K. CLEMENT, a citizen of the United States, residing at Laporte, in the county of Laporte and State of Indiana, have invented a new and useful 5 Grain-Sieve, of which the following is a specification.

My invention relates to sieves for cleaning and separating grain; and it has for its object to provide a device of this kind which may be quickly and readily changed so as to adapt it for different kinds and qualities of material to be operated upon, and thereby avoid the necessity of providing a separate 15 sieve for each kind of material.

As ordinarily constructed the threshing-machines which are used upon different varieties of grain require several different kinds of sieves, which must be changed or removed 20 from the machine whenever a change is made from one kind of material to another. Besides taking valuable time for making the changes and adjusting the machine to the different materials the owner of the machine 25 is compelled to carry a full complement or set of sieves, and if any of them becomes defective or broken they must be replaced before the machine can perform its proper functions.

My invention consists in a combined sieve 30 which can be quickly and easily adjusted, so as to adapt one sieve for use upon all the different varieties or grades of material which will be operated upon by the machine; and it consists in the improved construction and 35 novel arrangement of parts of such a sieve, as will be hereinafter more fully set forth.

In the accompanying drawings, in which the same reference-numerals indicate corresponding parts in each of the views in which 40 they occur, Figure 1 is a top plan view of my combined sieve. Fig. 2 is a longitudinal central sectional view of the same. Fig. 3 is a similar view at one side of the center, and Figs. 4 and 5 are detail views.

Referring more particularly to the drawings, 45 I indicates the main frame of my sieve, which is rectangular and of any suitable size for use upon a machine for which it is adapted. Arranged longitudinally at the center of the 50 frame is a bar 2, through which and through the ends of the frame is passed the screw-

threaded rod 3. Arranged transversely of the frame is a series of flat perforated plates 4 at a suitable distance apart and having their inner or central portions secured to and supported by the central bar 2. 55

Arranged upon the top of the frame 1 is an auxiliary frame 5, preferably formed from sheet metal and provided with strengthening-ribs 6 upon each edge and a central rib 7. 60 Each of these ribs is preferably triangular in cross-section, and the central one extends from end to end of the frame and has its upper edge provided with inclined notches 8. At each end of the central rib a substantially 65 U-shaped clamp 9 is secured, which extends beyond the ends of the main frame 1 and engages with the under side thereof, as shown in Fig. 2. The bottom portion of each one of these clamps is perforated in alignment 70 with the perforation through the central bar 2 for the passage of the rod 3. The ends of the rod beyond the clamps are provided with stops or shoulders 10 and 11, which engage with the clamps and move the auxiliary frame 75 back and forth as the rod is rotated by means of the handle 12 at one end, the intermediate portion of the rod being screw-threaded and passing through screw-threaded plates 13 upon the opposite ends of the main frame. 80

The central or main portion of the auxiliary frame is slotted transversely upon each side of the central rib 7 and has the slotted portion bent downward at an inclination to the main portion to form lips or deflectors 14, 85 which pass down through the spaces between the transverse strips of the main frame. The remaining flat portions of the auxiliary frame are perforated and of substantially the same width as the strips upon the main frame. 90 The auxiliary frame is provided upon each side with one more flat portion than there are flat portions on the main frame, so that when the frames are adjusted in one position all of the spaces will be covered or occupied by the 95 flat portions of the auxiliary frame, and when they are adjusted in the opposite position all of said spaces will be open. To permit of the adjustment or movement of the auxiliary frame to its full extent or limit in both directions, the end pieces of the main frame must be beveled or cut away, as shown at 15, for 100

the reception of the inclined wings or blades of the auxiliary frame.

As above described, my improved sieve can be put in a threshing-machine in the usual manner or it can be applied equally as well to the ordinary windmill or grain-separator. After it has been secured in position it is adjusted by turning the rod 3 until the auxiliary frame has been moved relatively to the main frame a sufficient distance to leave the desired space between the edge of the flat portion provided with the wings or blades and to bring it into the desired relation to the edge of the adjacent strip upon the main frame. When it is desired to use it with larger grain—as, for instance, oats—the openings between the strips of the two frames are made as wide as possible. For the small grains, as wheat and barley, the openings are made smaller, while for small seeds—such as flax, timothy, &c.—the openings are closed entirely, and the surface of the sieve is made substantially continuous except for the small perforations thereover. After the sieve has been once adjusted it will remain in that position until changed by rotating the rod 3, which must be done manually, thereby avoiding the possibility of the adjustment of the sieve changing after it has been set. In placing the sieve within the shoe the wings or blades are set so as to point toward the fan, and the handle of the rod is placed at the lower or outer end in convenient position for being rotated to adjust the sieve.

The sieve portions of the two frames are preferably formed from zinc or other non-corrosive material and provided with suitable sized perforations. It is evident, however, that they might be formed from any other metal or from woven wire having the desired mesh. It is also evident that other modifications might be made, and I reserve to myself the right to make such changes or alterations in the construction thereof as will come within the scope of my invention.

Having thus fully described my invention,

what I claim as new, and desire to secure by Letters Patent, is—

1. In a combined sieve, the combination, with two frames, each of which is provided with a central bar, the one within the main frame being perforated longitudinally, of a screw-threaded plate at each end of the main frame, a substantially U-shaped clamp secured to the ends of the bar on the movable frame, the central portion of which is perforated and registers with the perforation on the main frame and the free end extends to the opposite side of the main frame, a screw-threaded bolt through said perforation and said plates, each end of which is provided with a stop for engaging with the clamp, and one end is provided with a handle, substantially as described.

2. In a combined sieve, the combination, with two frames, each of which is provided with a central bar and one of them is provided with strengthening-ribs upon its edges, the ribs and bar upon the movable frame being triangular in cross-section and the bar being provided with inclined notches at its upper edge, each of the frames being provided with transversely-arranged perforated strips, and means for adjustably moving one frame upon the other and holding it in its adjusted position, substantially as described.

3. In a combined sieve, the combination, with a main frame, the ends of which are inclined or beveled, of perforated strips, an auxiliary frame provided with transversely-perforated strips, there being one more strip on the auxiliary frame than there are strips on the main frame, and one edge of each of said strips being provided with an inclined blade, and means for moving said auxiliary frame upon the main frame, substantially as described.

HENRY K. CLEMENT.
